POLYMERIZED HYDROCARBON OILS

Emmet R. Kirn and Nathan Fragen, Hammond,
Ind., assignors to Standard Oil Company, Chi-
cago, Ill., a corporation of Indiana

Application October 8, 1938, Serial No. 233,995

7 Claims. (Cl. 196—10)

This invention relates to the conversion of hydrocarbon gases into useful oils and particularly lubricating oils and gasoline. One of the objects of the invention is to convert the butane-butylene fraction of cracking still gases into high quality lubricating oils and motor fuels. Another object of the invention is to polymerize the unsaturated constituents of a four carbon atom fraction of said gases by means of a catalyst, thereby producing a product of wide boiling range and thereafter distilling said product into several fractions which are separately handled. Other objects of the invention will be set forth hereinafter.

The invention is illustrated by a drawing which shows diagrammatically a complete layout for carrying out the process. Referring to the drawing, a liquefied normally gaseous hydrocarbon stream is introduced by line 10 into reaction chamber 11. The hydrocarbon stream may suitably comprise a mixture of butanes and butylenes derived from the fractionation of cracking still gases. As an example of such a mixture, we may use one containing about 10 to 20% of isobutylene, about 20 to 30% of normal butylenes and the remainder mostly isobutane and normal butane. The gases may be washed with caustic soda or other reagent to remove H₂S or other sulfur compounds and with dilute acids to remove amines they may contain. Suitable unsaturated C₄ hydrocarbon gases may also be obtained from dehydrogenating butanes from natural gases.

In the reactor 11, there is also introduced by line 12 a stream of catalyst preferably boron fluoride. However, boron chloride and other catalytically active metal halides may be employed. The temperature of the reaction mixture in chamber 11 may be controlled by cooling coil 13, a suitable temperature being between 0 and 100° F., for example, 40° F. In the reaction chamber 11, the isobutylene contained in the hydrocarbons is polymerized by the catalyst, the reaction requiring about 5 to 30 minutes. The amount of catalyst may be suitably about 0.1 to 2% of the weight of the total hydrocarbons treated, 0.2 to 0.5% being commonly employed.

The reaction products are conducted by line 14 to washer 15 in which any excess catalyst or acid products, e. g., HF or HCl may be neutralized with water or alkali, for example sodium hydroxide. Thence the products are conducted by line 16 to stripper 17 in which the unreacted gases are vaporized and removed by line 18, heat being supplied by coil 19 and reflux by coil 20.

If desired, a gasoline fraction may also be removed by stripper 17.

The remaining products are conducted by line 21 and pressure reducing valve 22 to fractionator 23 which may be operated under partial vacuum. In fractionator 23, the product is separated into an over-head gas fraction and side fractions comprising gasoline, cycle oil, and a Diesel lubricating oil hereinafter more fully described. A residual heavy oil fraction is withdrawn by line 24 and conducted to depolymerizer 25 by pump 26. This residual heavy oil may be blended with the cycle oil to produce a high quality shock absorber oil if desired.

The gasoline fraction withdrawn by line 27 may be discharged from the system through valve 28 to receiver 27a and employed in the manufacture of high knock-rating gasolines. By proper adjustment of valves in lines 27, 46, 32 and 35, the gasoline fraction may be recycled to reactor 11 or it may be depolymerized in depolymerizer 25. A Diesel lubricating oil is withdrawn from the system by line 29 leading to receiver 29a. An intermediate fraction termed "cycle oil" is withdrawn by line 30 and conducted through valves 31 and 45 by line 32 to pump 33 which recycles it by line 34 to reactor 11. The introduction of cycle oil, consisting of hydrocarbons mostly within the range of 16 to 28 carbon atoms, along with fresh feed in reactor 11 yields additional amounts of hydrocarbon oil which boils in the Diesel lubricating oil range by modification of the polymerization reaction. If desired, valve 31 may be partially or fully closed and cycle oil may be transferred by line 35 and valve 36 and pump 26 to depolymerizer 25.

In the depolymerizer 25, the undesired by-products of the Diesel lubricating fraction are decomposed either by heat alone or by heating with a suitable catalyst which may be placed in chamber 37. When heat alone is employed, we prefer to operate at a temperature of about 600 to 1000° F. In the presence of catalysts, however, we may use temperatures of about 400 to 600° F., depending on the catalyst. Suitable catalysts are, for example, activated bentonite or a catalyst comprised of aluminum oxide adsorbed on silica gel.

Decomposition of the undesired by-products results in the formation of unsaturated hydrocarbons, both liquid and gases. Butylenes for example, are readily produced by the decomposition of corresponding butylene polymers, particularly polymers of isobutylene. In addition, some of the heavy hydrocarbons present in the residual

oil from fractionator 23 may be partially depolymerized to oils of intermediate viscosity which may subsequently be recovered as Diesel lubricating oils.

The depolymerized products from 25 and 37 are conducted by valved line 38 through cooler 39 and thence by line 34 to reactor 11 wherein unsaturated constituents, including the butylenes, are repolymerized to oils within the Diesel lubricating oil range together with other polymerization products. If desired, however, valve 49 may be closed and valve 41 opened to direct the depolymerization products by line 42 into fractionator 23. Here the products of depolymerization are subjected to distillation, heavy constituents being recycled to depolymerizer 25 by line 24 and pump 26. Lighter products of depolymerization are fractionated and separated into the desired Diesel lubricating oil which is withdrawn by line 29, cycle oil and gasoline. Gases, including butylenes, are conducted by line 43 and pump 44 to reactor 11 wherein they are again subjected to polymerization.

The Diesel lubricating oil withdrawn by line 29 is characterized by unusually high viscosity index, a low pour point, and low volatility, coupled with unusual freedom from sludge formation when subjected to high load conditions existing within Diesel engines. As a result of these properties, this oil, when employed for the lubrication of pistons of Diesel engines, enables these engines to be operated longer periods of time and under high load conditions without seizure or scoring of the pistons and cylinder walls which commonly results from carbonization of the piston rings by ordinary type oils. It is preferred to regulate the fractionation in tower 23 to produce Diesel oils having a viscosity within the range of about S. A. E. 20 to S. A. E. 50 and gravity of about 32° A. P. I. The oil is wax free and the pour point is about -30° F. for the oil of viscosity 30 S. A. E. The distilled Diesel lubricating oil may have a viscosity index of about 80 to 95 (Dean and Davis scale).

In order to make the heavier grades of Diesel lubricating oil distillates, we prefer to carry out the fractionation in two stages instead of one stage as illustrated by tower 23. By employing another stage of distillation, we prefer to conduct the fractionation in 23 at atmospheric pressure, removing gasoline and perhaps cycle oil. The remaining products, including the desired Diesel lubricating oil, may be conducted by line 24a to fractionator 23a, preferably operated under high vacuum where the Diesel lubricating fraction is removed as a distillate by line 29b and the residue is sent to heater 25 by line 24b and pump 26.

As an example, a residue from fractionator 23 was distilled continuously at about 12 mm. (mercury) pressure, absolute. The distillate was taken off at about 485 to 520° F., the temperature at the bottom of the vacuum tower being about 565 to 590° F. The distillate was a typical Diesel lubricating oil of 30 S. A. E. grade. The Saybolt viscosity was between 500 and 625 sec. at 100° F. and the gravity, 31.6 to 32.7 A. P. I. Variations are due largely to the difference in feed stocks and variations in the polymerization reaction conditions.

One of the outstanding characteristics of our invention is the flexibility in operation obtained in the process, depending on the character and the amount of the products desired. Thus, the distillation in fractionator 23 may be regulated

to produce Diesel lubricating oil of a wide range of viscosities, for example, 20, 30, 40 or 50 S. A. E. viscosity. Likewise, the conditions of polymerization in reactor 11 may be varied to alter the character of the polymerization products. It is preferred to conduct the polymerization in reactor 11 at temperatures within the range of 0 to 100° F., the preferred temperature being about 40 to 60° F. Higher temperatures encourage the formation of lighter polymers, thus increasing the yield of gasoline, cycle oil and light Diesel lubricating oil. Likewise, the recycling of undesired polymerization products and depolymerized products may be varied as described to modify the reaction in polymerizer 11. Thus, recycling the depolymerized products by line 42 to fractionator 23 results in an increase of the isobutylene and light olefin concentration in 11 by introduction of these light products through line 43. On the other hand, recycling polymerization products by lines 32 and 34 decreases the concentration of light or normally gaseous olefins in polymerizer 11. The reaction in 11 is accordingly modified, resulting in the formation of polymerization products of lower average molecular weight.

It should be understood that the gasoline, cycle oil, and Diesel lubricating oil fractions withdrawn from the fractionator 23 by lines 27, 30, and 29, respectively, may be subjected to stripping in the customary manner in order to remove undesirable low boiling constituents from each product. The gasoline fraction collected in receiver 21a may have a knock-rating of about 75 to 90 octane number (C. F. R. motor method) and it may be subjected to suitable hydrogenation to remove olefin constituents when employed for aviation engine fuel.

In carrying out the depolymerization in 25, 40 the time of heating may be varied from a few seconds to several minutes. For example, with a contact time of 10 to 100 seconds and a temperature of 929° F. at atmospheric pressure, the product contained 20 to 30% of C₄ fraction, 45 largely isobutylene. If the polymer oil, particularly the lighter cycle oil, is heated for a longer time, lower temperatures may be used. Thus, at 600 to 610° F., 21% decomposition occurred in 23 minutes.

Although we have described our process with respect to certain embodiments thereof, we intend that it be limited only by the following claims.

We claim:

1. In the process of converting normally gaseous olefin hydrocarbons into distillate lubricating oil, the method of increasing the yield of said oil which comprises subjecting said olefin hydrocarbons in liquid phase to the action of a polymerizing catalyst whereby said olefins are converted into heavier hydrocarbon polymers, separating unreacted gaseous hydrocarbons from said polymers, fractionating said polymers in a fractionating zone, and producing said desired distillate lubricating oil and a substantially non-volatile residue, subjecting said residue to pyrolytic decomposition regulated to regenerate olefinic hydrocarbons and to produce lubricating oils of intermediate viscosity boiling within the range of said desired distillate lubricating oil, recycling the products of said decomposition to said fractionating zone and modifying the polymerization of said olefinic hydrocarbons by recycling at least a portion of the products of said decom-

position from said fractionating zone to the catalytic polymerization step first mentioned.

2. The process of claim 1 wherein the polymerizing catalyst employed is boron fluoride.

3. The process of claim 1 wherein the normally gaseous olefin hydrocarbon starting material comprises a cracking still hydrocarbon gas mixture.

4. The process of converting olefinic hydrocarbon feed gases into a distillate Diesel lubricating oil and a high knock rating gasoline, which comprises polymerizing said olefinic hydrocarbons in liquid phase in the presence of an active metal halide catalyst whereby polymerization products of a wide range of molecular weight are produced, separating said polymerization products from unreacted gases, fractionating said polymerization products in a fractionating zone into gasoline, cycle oil, Diesel lubricating oil, and a residual oil fraction, depolymerizing said residual oil fraction to produce unsaturated products capable of further polymerization, introducing said depolymerization products into said fractionating zone at a point below the point of withdrawing said Diesel lubricating oil fraction, and recycling unsaturated depolymerization products from said fractionating zone to said catalytic polymerization step first mentioned, thereby modifying the polymerization of said olefinic hydrocarbons.

5. The process of claim 4 wherein said last-mentioned depolymerization products are normally gaseous hydrocarbons.

6. The process of converting normally gaseous olefin hydrocarbons substantially entirely into a desired distillate lubricating oil and high knock-rating gasoline by the process of polymerization, which comprises subjecting said olefins in a liquid phase to the action of a polymerizing cata-

lyst at a temperature between 0 and 100° F., separating unreacted paraffinic gases from the polymerization products, fractionating the polymerization products in a fractionating zone and withdrawing therefrom said desired gasoline fractions and distillate lubricating oil fraction, subjecting the remaining fractions of said polymerization products to thermal depolymerization, thereby producing additional amounts of normally gaseous olefins, gasoline and desired distillate lubricating oil, and recycling said depolymerization products to said fractionating zone wherein said gasoline and distillate lubricating oil resulting from depolymerization are fractionated and combined with the gasoline and distillate lubricating oils produced by said catalytic polymerization reaction.

7. The process of converting a mixture of butane and butylene hydrocarbons into high viscosity index distillate lubricating oil and high knock rating motor fuel which comprises polymerizing said butylenes into a wide range of polymers by treating said hydrocarbon mixture with a polymerizing catalyst, removing unreacted butane and butylenes, fractionating said polymers in a fractionating zone into a gasoline fraction, a distillate lubricating oil fraction and a heavy residual oil fraction, subjecting said heavy residual oil fraction to decomposition whereby butylenes are formed, recycling the products of said decomposition to the said fractionating zone, and recycling reformed butylenes from said fractionating zone to said polymerization operation where they are converted into additional amounts of said desired high viscosity index distillate lubricating oil.
